WHEELED TOY

Filed Nov. 9, 1928

Peter Strong

ATTORNEYS

UNITED STATES PATENT OFFICE

PETER STRONG, OF WINCHENDON, MASSACHUSETTS

WHEELED TOY

Application filed November 9, 1928. Serial No. 318,213.

My said invention relates to a figure wheeled toy of the type in which, when it is drawn along the ground, the rotation of the wheels imparts motion to the figure.

The invention aims to provide a toy of this character which may be very economically manufactured, which will be durable in use, and which will present an amusing and attractive appearance.

With these and other objects in view, the invention includes the novel construction and arrangement and combination of parts hereinafter described, the invention being defined by the claims appended hereto.

What I at present consider the preferred embodiment of the invention is illustrated in the accompanying drawing, in which

Figure 1 is a side elevation of the toy, showing it in raised position in dotted lines.

Fig. 2 is a rear elevation, and

Fig. 3 is a detail.

Referring by reference characters to this drawing, the numeral 1 designates a suitable platform preferably of wood and having depending side flanges 1^a in which are journaled the axles 2^a and 3^a of the front and rear wheels 2 and 3 respectively.

Supported upon the platform is an animal figure, shown as a desirable form as the figure of a rabbit having a body 4 and head 4^a preferably formed integral and having rear legs 4^b, front legs 4^c, ears 4^d and tail 4^e, all articulated to the body in the manner hereinafter described. The rear legs are fixedly secured to the platform, preferably by being set into grooves 1^b therein and secured by glue or the like, and these legs carry rigidly connected to their upper ends a pivot pin b which passes loosely through a cylindrical opening in the body so as to form a pivot bearing therefor. The rear end of the body is connected by a link or pitman 5 with the crank 3^x of the axle 3^a, so that as the crank revolves as the toy is pulled along the floor, the body of the animal is caused to rise and

fall, due to its pivotal support on the pin b carried by the fixed legs 4^b. The upper end of the link is connected to the body just below the tail 4^e (which is pivoted to the body by pin e) by suitable means such as a staple 5^a, and the link may have an extension 5^b which, as the body rises, will engage the tail and elevate the same, or the tail may be left free to be oscillated by the rapidity of movement of the body.

The body is made hollow, preferably by securing together two similar parts hollowed out on their inner faces. The pivot pin b is rigidly connected to the legs and rotatably engages the body by passing freely or loosely through openings in the walls thereof. The front legs and ears are likewise fast to the ends of the pivot pins c and d respectively, which pass through openings in the walls of the body and head, and the pivot pins b, c and d are all connected by a rod 6 which has pivotal connections b', c', d' to the pins b, c and d but offset from the axes thereof. The result of this is that as the body rises, point of connection b' being stationary, the pins c and d are rocked, thus swinging the front legs back and ears forward, and vice versa.

I claim:

1. A toy comprising a wheeled platform and an animal figure thereon, said animal figure having rear legs rigidly connected to the platform, a hinge pin rigidly connected to the legs and pivotally supporting the body of the figure, the front legs of the figure having a pivot pin rigidly connected thereto and pivotally engaging the body, said figure having ears, a hinge pin rigidly connected to said ears and pivotally engaging the head of the figure, wheel operated means for swinging the body on the pivot of the rear legs, and a link having offset connections to the pivots of the rear and front legs and ears respectively.

2. A toy comprising a wheeled platform,

- the rear wheels having a cranked axle, an animal figure having rear legs rigidly secured to the platform and a body articulated on said legs, said animal figure having a pivoted tail, a link connecting the rear of the body just below the tail with the crank on the axle, the upper end of said link having a rigid angularly extending projection to engage beneath and actuate the tail.
- 10 3. A toy according to claim 1 in which the three hinge pins are disposed in a common plane and the link comprises a straight bar overlying the pivot pins and pivotally connected directly thereto.
- 15 In testimony whereof I affix my signature.
PETER STRONG.
